COUNTER DISPLAY RACK

Daniel E. Gelles, 1140 Broadway,
Kerhonkson, N.Y. 10001

Filed June 16, 1966, Ser. No. 2,700

Term of patent 14 years

(Cl. D80—10)

I claim:

The ornamental design for a counter display rack, substantially as shown and described.
